UNITED STATES PATENT OFFICE

156,092

DESIGN FOR A GEM SETTING

Morris Goodman, Indianapolis, Ind.

Application March 5, 1949, Serial No. 1,251

Term of patent 14 years

(Cl. D45—1)

To all whom it may concern:

Be it known that I, Morris Goodman, a citizen of the United States, residing at Indianapolis, in the county of Marion and State of Indiana, have invented a new, original, and ornamental Design for Gem Setting, of which the following is a specification, reference being had to the accompanying drawing forming a part thereof,

Fig. 1 is a top plan view of a gem setting, drawn to a substantially enlarged scale, and showing my new design;

Fig. 2 is a front elevational view thereof to the same scale;

Fig. 3 is a sectional view thereof taken substantially on the line 3—3 of Fig. 1; and

Fig. 4 is an end elevational view thereof.

I claim:

The ornamental design for a gem setting, as shown.

MORRIS GOODMAN.
